UNITED STATES PATENT OFFICE.

THEOPHIL J. FREDA, OF DETROIT, MICHIGAN.

SURFACE-EXCAVATING MACHINE.

Application filed January 3, 1922. Serial No. 526,605

To all whom it may concern:

Be it known that I, THEOPHIL J. FREDA, a citizen of the United States of America, residing at Detroit, in the county of Wayne and State of Michigan, have invented certain new and useful Improvements in Surface-Excavating Machines, of which the following is a specification, reference being had therein to the accompanying drawings.

10 This invention relates to a surface excavating machine that may be advantageously used for road building, ground leveling purposes and large excavations.

My invention aims to provide a surface 15 excavating machine embodying a tractor provided with rotary cutters and conveyors by which earth may be expeditiously and economically removed from the surface and loaded in vehicles. The machine is particularly characterized by a novel arrangement 20 of transversely disposed rotary cutters which discharge earth into transversely disposed screw conveyors and from these conveyors endless belt or apron conveyors carry the earth forwardly and discharge the same into hoppers or chutes that may be positioned so that vehicles may receive earth from the same. In addition to the transversely disposed cutters, there are central cutters and 25 a central bucket conveyor and the transverse arrangement of the cutters is such that a wide section of earth can be removed as the machine is moved forward.

Other advantages of the surface excavating machine will appear as the invention is 30 described by the aid of the accompanying drawings, wherein

Figure 1 is a side elevation of the surface excavating machine, showing a vehicle that 35 may receive earth from the machine;

Fig. 2 is a plan of the machine;

Fig. 3 is a front elevation of a portion of the machine showing the transverse rotary cutters;

Fig. 4 is a plan of an arch member of the machine;

Fig. 5 is a central enlarged transverse sectional view of a portion of the machine, illustrating a power transmission and power controlling devices;

Fig. 6 is a diagrammatic sectional view on a small scale, and taken on the line VI-VI of Fig. 5;

Fig. 7 is a similar view taken on the line VII-VII of Fig. 5; 55

Fig. 8 is a cross sectional view of a portion of the construction shown in Fig. 5, and taken on the line VIII-VIII of Fig. 5;

Fig. 9 is an enlarged longitudinal sectional view of a portion of a rotary cutter, 60 showing the spiral or screw conveyor;

Fig. 10 is a cross sectional view of the line taken on the line X-X of Fig. 9;

Fig. 11 is a perspective view of a portion of one of the inner heads of one of the 65 rotary cutters, and

Fig. 12 is a detail sectional view of a portion of one of the inner heads of the machine;

Fig. 13 is a cross sectional view of a 70 bucket conveyor and

Fig. 14 is a perspective view of a portion of one of the rotary cutters.

Reference will first be had to Figs. 1 and 2 which gives some idea of the general appearance of the machine and in providing a framework for the machine I use, as far as possible structural steel of standard shapes so that the framework may be fabricated at a comparatively small cost and at the 75 same time insure the strength and rigidity necessary for machines of this type.

The reference numeral 1 denotes a substantially rectangular tractor frame provided with caterpillar traction members 2 80 of a conventional form, and on the rear end of the frame is a seat 3 for an operator or attendant of the machine.

4 denotes a superposed frame on which is placed an electric motor 5 or other source 85 of power, said motor having its armature shaft 6 provided with sprocket wheels 7 and 8, the latter being employed with sprocket chains 9 for driving the traction members 2, said sprocket chains being 90 trained under sprocket wheels 11 on one of the axles or drive shafts of the traction members 2.

10 denotes a forwardly extending frame 95 having its rear end suitably mounted on the tractor frame 1 and the forward end of the frame 10 is supported by pony trucks 12 and 13. At the extreme forward end of said frame 10 is an overhanging portion or bracket 14 under which a vehicle 15, as a 100 truck, may be backed to receive earth from

hoppers or chutes 16 and 17 carried by the overhanging portion 14 of the frame 10. The hoppers 16 are two in number, one at each side of the overhanging bracket 14, and the hopper 17 is in advance of the transverse plane of the hopper 16 and elevated compared thereto.

The main frame 10, intermediate the ends thereof, is connected by transverse supports 18 and connecting these supports intermediate the ends thereof, is a longitudinally disposed arch member 19 provided with openings 20. On the arch member is a bearing 21 and a bearing 22, said bearings supporting a shaft 23 provided with a sprocket wheel 24 longitudinally alining with the sprocket wheel 7 of the motor armature shaft 6, so that an endless sprocket chain 25 may be trained over the sprocket wheels 7 and 24 for driving the shaft 23.

Mounted on the shaft 23, within the bearing 21, is a sprocket wheel 26 and suitably connected to the lower face of the bearing 21 is a hanger 27. Extending through the hanger 27 are a plurality of circumferentially arranged tie rods 28 and mounted on the ends of said tie rod are inner heads 29 having bottom pieces 30 connected below the hanger 27. Some of the rods 28 connect the inner heads 29 and the hanger 27 with outer heads 33, but the lowermost rods 28, are of less length, simply connecting the inner heads, so as not to obstruct falling earth.

Connected to the inner heads 29 are the end flanges 31 of outwardly extending transversely alining conduits or tubes 32 which have the outer ends thereof provided with the outer bearing heads 33 containing concentric anti-frictional radial and end thrust bearings 34 and similar circumferentially arranged bearings 35.

Concentric of each conduit or tube 32 is a rotatable conveyor shaft 36 which has its ends journaled in the heads 29 and 33 and on said shaft is a spiral conveyor or screw 37 which is driven to conduct earth from the inner end of the conduit 32 to the outer end thereof. Loose on the inner end of the shaft 36 is a sleeve 38 and fixed on said sleeve is a large gear wheel 38 and a small gear wheel 39. The large gear wheel 38 meshes with a plurality of small circumferentially disposed gear wheels 40 mounted on longitudinally disposed shafts 41 journaled in the inner head 29 and the bearings 35 of the outer head 33. On these shafts, at intervals, are pinions 42 meshing with internal racks 43 forming part of rotary longitudinally disposed cutters 46 connected by a skeleton framework so that earth may fall therethrough when conducted to the upper side of each cutter. The skeleton framework includes longitudinal webs 45 and circumferentially disposed

webs 44 at the inner edges of which are the racks 43. Formed integral with the webs 45 and the cutters 46 are cutter connecting ribs 44, and by reference to Figs. 10 and 14 it will be observed that the ribs 44 brace the inner and outer walls of the cutters 46. The cutters form scoops or shovels into which earth may be gathered and carried upwardly to the upper side of the rotary cutter where it will be discharged from the scoops or shovels, through the framework of the cutter into the conduit 32, the discharged earth passing through a series of openings 48 in the upper side of the conduit 32, said opening having longitudinal deflectors 49 fixed on the edges of the conduit 32 to deflect earth into the conduit.

The cutters 46 afford major teeth and each major tooth has saw tooth edges or minor teeth 51 which are adapted to easily enter the earth and loosen or disintegrate the same so that the earth may be scooped up by the cutter shovels.

One or more of the cutters 46 may be provided with pivoted contact arms 52 extending beyond the path of travel of the cutter so that should a rock or other indurate obstruction 53 be encountered, an electrical circuit may be established by leading out wires 54 to display or sound a visible or audible signal (not shown). The operator of the machine will therefore be warned of such an obstruction and give the machine his entire attention for fear that it may be necessary to stop the rotary cutter which will eventually encounter the obstruction.

The innermost rack 43 of each rotary cutter has auxiliary cutters 55 connected thereto, said auxiliary cutters being below the arch member 19 and adapted to deflect earth outwardly and into the inner ends of the conduits 32.

The small gear wheels 39 mesh with large gear wheels 56 loosely mounted on a shaft 57, journaled in side frames 58 carried by the bottom pieces 30. The gear wheels 56 have clutch members 59 adapted to be engaged by adjustable clutch members 60 slidably keyed on the shaft 57 for rotation therewith and said clutch members are adapted to establish driving relation between the shaft 57 and the gear wheels 56. The shaft 57 extends through the hanger 27 and is provided with fixed gear wheels 61 which have the hub portions thereof journaled in the hanger 27. Fixed on the shaft 57 within the hanger 27 is a large sprocket wheel 63 vertically alining with the sprocket wheel 26 and about said sprocket wheels is trained an endless sprocket chain 64, said chain extending through openings 65 of the arch member 19.

The clutch members 60 may be shifted by levers 66 and 67 extending through the

openings 20 of the arch member 19, the lever 67 being pivotally mounted, as at 68, in one of said openings and pivotally connected, as at 69, to the lever 66 whereby manipulation 5 of said lever will cause the adjustable clutch members 60 to engage the clutch member 59 of the gear wheels 56.

The side frames 58 and the hanger 27 co-operate in supporting rotatable shafts 70 10 on which are mounted gear wheels 71 meshing with the gear wheels 61, and the gear wheels 71 mesh with gear wheels 72 fixed on a shaft 73, the gear wheels 72 having the hub portions thereof journaled in the hanger 27 15 and the side frames 70. The shaft 73 may be coupled to the conveyor shafts 36 or all three shafts may be a single shaft extending from one outer bearing head 33 to the other. Separate shafts will permit of parts of the 20 machine being easily assembled or repaired.

Journalized in the lower end of the hanger 27 and the side flange 58 is a set of shafts 74 and loose on said shafts are sets of gear wheels 75 meshing with the gear wheels 72 25 and with the cogs or teeth 76 of an endless apron or belt 77 provided with scoops or buckets 78 affording a bucket conveyor in the longitudinal vertical plane of the machine. The bucket conveyor is trained under anti-frictional rollers 79 supported from 30 the bottom pieces 30 so that the buckets 78 may pass between the auxiliary cutters 55, as best shown in Fig. 5, and these buckets are adapted to scoop up such earth as is loosened between the auxiliary cutters. The bucket conveyor extends over an anti-frictional roller 80 above the arch member 19; a similar roller 81 supported above the main frame 10, and other rollers 82 supported by 35 a scaffold 83 carried by the overhanging frame or bracket 14 and extending over the hopper or chute 17, so that earth may be discharged into said hopper during the operation of the machine. The scaffold 83 and 40 the supports 84 of the roller 80 may be braced by tie rods or cables 85 relative to the main plane 10 of the machine.

At the outer ends of the conduits 32 are discharge openings 86 and earth conducted 45 to the outer ends of said conduits falls through the openings 86 on to endless apron conveyors, 87, said apron conveyors being trained about rolls 88 and 89, the former being one of the shafts 41 of each rotary cutter and the latter on a shaft 90, journaled in bearings 91 at the side hoppers or chutes 16. The apron conveyors 87 extend upwardly at an inclination, as best shown in Fig. 1, and are driven in synchronism with the rotary cutters so that as fast as earth is removed it may be conveyed to the hoppers 16.

Considering Fig. 5, it will be noted that the central bucket conveyor is driven through the medium of the shafts 23, 57 and 53 and since the shaft 73 forms part of the

shafts 36 the spiral conveyors will be operated in synchronism with a bucket conveyor.

It is through the medium of the levers 66 and 67 that the clutches 60 may fix the gear wheels 56 relative to the driven shaft 57 so 70 that power may be transmitted to the shafts 41 and thus operate the rotary gears.

While in the drawing there is illustrated a preferred embodiment of my invention, it is to be understood that the structural elements are susceptible to such variations and modifications as fall within the scope of the appended claims.

What I claim is:—

1. A surface excavating machine comprising a tractor, a main frame supported thereby and overhanging unexcavated ground, transversely disposed spaced apart rotary cutters supported by said main frame, a conveyor axially of each cutter and of greater 80 length than each cutter adapted to conduct earth to the outer end of each cutter, and means on said tractor adapted to simultaneously operate said cutters and conveyors.

2. A surface excavating machine as in 90 claim 1, wherein said means transmits power to the inner ends of said cutters and conveyors.

3. A surface excavating machine as in 95 claim 1, and endless apron conveyors at the outer ends of said cutters adapted to receive earth from the conveyors axially of said cutters and conduct earth to the forward end of said main frame.

4. A surface excavating machine as in 100 claim 1, and bucket conveyors between said cutters and adapted to convey earth to the forward end of said main frame.

5. A surface excavating machine as in 105 claim 1, wherein each cutter is composed of a framework having webs between which earth may fall on to said conveyors.

6. A surface excavating machine as in 110 claim 1, wherein the conveyors are in the form of screws disposed in conduits with conveyor operating means between the inner ends of said conduits and from the outer ends of which conduits earth is discharged by said conveyors.

7. A surface excavating machine comprising a tractor, a main frame supported thereby, rotary cutters disposed transversely of said main frame, spiral conveyors axially of said cutters adapted to conduct earth to the outer ends of said cutters, hoppers supported 115 from the forward end of said main frame, and endless conveyors adapted to conduct earth from the outer ends of said spiral conveyors to said hoppers.

8. A surface excavating machine as in 120 claim 7, wherein the hoppers are elevated so that a vehicle may back under said hoppers to receive earth therefrom.

9. A surface excavating machine as in 125 claim 7, and an endless bucket conveyor 130

1. A surface excavating machine as in claim 1, and means on said main frame adapted to conduct earth from between said cutters to one of said hoppers.
2. A surface excavating machine as in claim 1, and means operated from said tractor and including gear wheels adapted for simultaneously operating said cutters and spiral conveyors with one of said gear wheels transmitting power to said endless conveyor.
3. A surface excavating machine as in claim 1, wherein the tractor is adapted to move on an excavated surface and pony trucks under the forward end of said main frame engaging an unexcavated surface co-operate with said tractor in supporting said cutters relative to the unexcavated surface.
4. A surface excavating machine comprising a main frame, transversely disposed coaxial rotary cutters supported by said main frame, and having confronting ends in spaced relation, conduits axially of said cutters, spiral conveyors in said conduits and adapted to conduct earth to the outer ends of said conduits, and means between the confronting ends of said cutters adapted to simultaneously operate said spiral conveyors, bucket conveyor and said cutters.
5. A surface excavating machine as in claim 4, and means supporting the forward and rear ends of said main framework, so that said framework may be advanced on excavated and unexcavated ground during the operation of said cutters.
6. A surface excavating machine as in claim 4, and endless conveyors adapted to conduct earth forwardly from the outer ends of said conduits and from between said cutters.
7. A surface excavating machine comprising a main frame, transversely disposed rotary cutters, conduits axially of said cutters and adapted to receive earth therefrom, spiral conveyors in said conduits adapted to discharge earth at the outer ends thereof, means between said cutters for simultaneously operating said cutters and conveyors, and means between said cutters operated by the last mentioned means adapted for excavating earth and removing earth from between said cutters.
8. A surface excavating machine, as in claim 7, wherein the last mentioned means includes auxiliary cutters operable in unison with said rotary cutters, and an endless bucket conveyor between said auxiliary cutters.
9. A surface excavating machine comprising a main frame, transversely disposed rotary cutters carried thereby, means axially of said rotary cutters adapted to receive and conduct earth to the outer ends of said cutters, and earth removing means disposed between said cutters.
10. A surface excavating machine as in claim 7, and means on said main frame adapted to simultaneously operate said cutters.
11. A surface excavating machine as in claim 7, and means supporting the forward end of said main frame on unexcavated ground and the rear end of the main frame on excavated ground so that it may be advanced during the operation of said cutters.
12. A surface excavating machine as in claim 7, wherein the tractor is adapted to move on an excavated surface and pony trucks under the forward end of said main frame engaging an unexcavated surface co-operate with said tractor in supporting said cutters relative to the unexcavated surface.
13. A surface excavating machine comprising a main frame, transversely disposed coaxial rotary cutters supported by said main frame, and having confronting ends in spaced relation, conduits axially of said cutters, spiral conveyors in said conduits and adapted to conduct earth to the outer ends of said conduits, and means between the confronting ends of said cutters adapted to simultaneously operate said spiral conveyors, bucket conveyor and said cutters.
14. A surface excavating machine as in claim 13, and means supporting the forward and rear ends of said main framework, so that said framework may be advanced on excavated and unexcavated ground during the operation of said cutters.
15. A surface excavating machine comprising a main frame, transversely disposed rotary cutters, conduits axially of said cutters and adapted to receive earth therefrom, spiral conveyors in said conduits adapted to discharge earth at the outer ends thereof, means between said cutters for simultaneously operating said cutters and conveyors, and means between said cutters operated by the last mentioned means adapted for excavating earth and removing earth from between said cutters.
16. A surface excavating machine, as in claim 15, wherein the last mentioned means includes auxiliary cutters operable in unison with said rotary cutters, and an endless bucket conveyor between said auxiliary cutters.
17. A surface excavating machine comprising a main frame, transversely disposed rotary cutters carried thereby, means axially of said rotary cutters adapted to receive and conduct earth to the outer ends of said cutters, and earth removing means disposed between said cutters.
18. A surface excavating machine, as in claim 17, and means on said main frame adapted to simultaneously operate said cutters.
19. A surface excavating machine as in claim 17, and means supporting the forward end of said main frame on unexcavated ground and the rear end of the main frame on excavated ground so that it may be advanced during the operation of said cutters.
20. In a surface excavating machine, a rotary skeleton framework, rows of rigid cutter teeth on said rotary skeleton framework, ribs connecting said teeth and bracing the walls thereof, a stationary conduit in said rotary skeleton framework and into which earth may fall, and means in said rotary skeleton framework and supported on said conduit for imparting rotation to said framework.
21. An excavator comprising inner and outer heads, circumferentially disposed shafts rotatably supported by said heads, a rotary cutter about said shafts and driven therefrom, and a conduit connecting said heads and adapted to receive earth from said cutter, said conduit supporting said outer head relative to said inner head and at intervals supporting said shafts.
22. An excavator as called for in claim 21, wherein said cutter is in the form of a framework having rigid rows of teeth disposed to scoop up earth.
23. An excavator as called for in claim 21, and a conveyor at the outer head and extending rearwardly from said conduit adapted to receive earth from said conduit said conveyor being operated from one of said shafts.
24. An excavating machine comprising sets of heads coaxially disposed, shafts journaled in each set of heads, cutters disposed circumferentially of said shafts and driven thereby, auxiliary cutters at the inner ends of the first mentioned cutters, a conveyor between said sets of heads, and means between said sets of heads for simultaneously driving said shafts and said conveyor.
25. An excavating machine as called for in claim 24, and means operated from between the sets of heads for conveying earth axially of said cutters.
26. An excavating machine comprising coaxially arranged rotary cutters, racks at the inner ends of said cutters for revolving said cutters, auxiliary cutters carried by said racks, and driving means for said racks arranged between the inner ends of said cutters.
27. An excavating machine as called for in claim 26, and a conveyor operated in synchronism with said racks and adapted to receive earth from said auxiliary cutters.
28. In a service excavating machine, transversely alining rotary bucket-like cutters

each including framework having webs and adapted to move earth along the bottom a rack, and means at the confronting ends walls of said conduit and adapted to be of said cutters engaging the racks thereof operated independent of said cutters.

- 5 29. In a surface excavating machine, a conduit adapted to receive excavated earth, rigid cutters disposed circumferentially of said conduit and longitudinally thereof, a framework supporting said cutters about 10 said conduit and including webs and a rack with cutters integral with said webs, and means engaging the rack of the framework adapted to rotate said framework and said cutters about said conduit.
- 15 30. A surface excavating machine as called for in claim 29, and rotary means
31. In a surface excavating machine, 20 transversely alining rotary cutters, means internally of said cutters and including a series of shafts and pinions for rotating said cutters, and means between the confronting ends of said cutters for transmitting power to the first mentioned means. 25

In testimony whereof I affix my signature in presence of two witnesses.

THEOPHIL J. FREDA.
